CLAIM

The ornamental design for a writing utensil as shown and described.

DESCRIPTION

FIG. 1 is a perspective view of the writing utensil; FIG. 2 is a right side view of the writing utensil of FIG. 1; FIG. 3 is a top view of the writing utensil of FIG. 1; FIG. 4 is a left side view of the writing utensil of FIG. 1; FIG. 5 is a bottom view of the writing utensil of FIG. 1; FIG. 6 is a front view of the writing utensil of FIG. 1; and, FIG. 7 is a rear view of the writing utensil of FIG. 1.

The writing utensil is shown with symbolic breaks in its length. The appearance of any portion of the article between the break lines forms no part of the claimed design. The dash-dash broken lines in the drawings represent portions of the writing utensil that form no part of the claimed design. The dot-dash broken lines define the bounds of the claimed design and form no part thereof.
